WATER POLO GOAL OR THE LIKE

Anton J. Kajlich, 30 Crystal Cove,
Laguna Beach, Calif. 92651

Filed Aug. 16, 1972, Ser. No. 280,979

Term of patent 14 years

Int. Cl. D21—02

U.S. Cl. D34—5 VV

FIG. 1

FIG. 3

FIG. 4

FIG. 1 is an isometric view of the water polo goal showing my new design, taken from an upper side location forward of the goal;

FIG. 2 is a view similar to FIG. 1, but taken from a location behind the goal;

FIG. 3 is a top plan view of the goal; and

FIG. 4 is a sectional view taken along line 4-4 of FIG. 3.

I claim:

The ornamental design for a water polo goal or the like, as shown.
